DESIGN FOR A SHOE

John Rushforth Garside, Jr., Mamaroneck, N. Y.

Application November 12, 1934, Serial No. 53,986

Term of patent 3½ years

To all whom it may concern:

Be it known that I, John Rushforth Garside, Jr., a citizen of the United States, residing in Mamaroneck, in the county of Westchester and the State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevation of the shoe, partly in perspective.

I claim:

The ornamental design for a shoe, as shown.

JOHN RUSHFORTH GARSIDE, JR.
